DOOR CHECK

Rex C. Jacobs, Detroit, Mich., assignor to Shelving and Parts Manufacturing Corporation, Detroit, Mich., a corporation of Michigan

Application July 29, 1935, Serial No. 33,636

7 Claims. (Cl. 16—85)

The present invention pertains to door checks adapted for use in combination with automobile doors and pertains more particularly to door checks such as disclosed in my co-pending applications Serial No. 23,352 filed May 25, 1935 and Serial No. 33,637, filed July 29, 1935, which have now matured into Patents Nos. 2,039,960 and 2,039,961 respectively, both dated May 5, 1936.

10 The primary object of the present invention is to provide means for limiting swinging movement of an automobile door with respect to an automobile body, the checking means being in the nature of a cushioning device so as to avoid 15 an abrupt checking action and the stresses and strains to which the door and its supports are subjected when the door is abruptly checked.

The present check is formed of a strap-like blank of spring metal and has one end provided 20 with a loop through which a pin is passed, the pin being supported in brackets on the door or on the door jamb, the particular illustration here presented illustrating the brackets and pin as being on the door. The other end of the 25 strap member is bent for engagement with a retainer element supported in the door jamb, the bent formation of the strap being such that it provides the desired cushioning action above referred to. These structural features are common 30 to the structure shown in my Patent No. 2,039,960 referred to above and in one respect this application is an improvement thereon. Fatigue tests have indicated that the present type of door check breaks at substantially the 35 point where the strap member is bent to start the formation of the loop and this invention has as an important object to reinforce the loop formation and to thus increase the useful life of such door checks.

40 With the above and other ends in view the invention is more fully disclosed with reference to the accompanying drawing, in which—

Figure 1 is a cross section illustrating the door check in assembled relation with a door and door jamb;

45 Fig. 2 is a similar view illustrating other stages in the operation of the check;

Fig. 3 is a plan view of the door check prior to assembly in a door;

50 Fig. 4 is a fragmentary elevation illustrating a detail, and

Fig. 5 is a section illustrating another detail.

Like characters of reference are employed throughout to designate corresponding parts.

55 The numeral 1 designates a door jamb hav-

ing an opening 2 formed therein. Secured to the inner surface of the door jamb 1 and covering the opening 2 is a socket member 3. The rear wall 4 is angularly disposed with respect to the plane of the door jamb 1 and is provided with an aperture 5. A door 6 is hingedly supported with respect to the jamb 1 by a hinge 7. The door 6 is provided with a pair of spaced apart lugs 8 supporting a pin 9, one of the lugs being illustrated in the drawing.

10 The above described construction constitutes a support for the present door check which is formed by bending a strap-like blank of spring metal to the desired shape. The strap-like blank is bent to provide a loop for the reception 15 of the pin 9 for the purpose of attaching one end of the check to the door. This loop is designated by the numeral 10 but instead of making the loop 10 a complete circle, as in my Patent No. 2,039,960 referred to above, the end of the blank 20 is provided with a straight run 11 extending tangential to the periphery of the pin 9. The extremity of the run 11 is provided with a notch 12. Extending from the loop 10 is an arcuate or bowed run 13, the latter being projected 25 through the aperture 5. The bowed run 13 terminates in an outwardly bent run providing a shoulder 14 and continuing from the shoulder 14 the blank is bent to provide a spring loop 15. The spring loop 15 terminates in a shoulder 16 30 from which extends a substantially straight run 17. At the termination of the straight run 17 is provided a short run 18 which extends outwardly at an angle with respect to the run 17 and opposed to the shoulder 16 and thus constituting another shoulder. From the shoulder 18 the blank is bent to provide a bowed run 19, the terminal of which is lanced to provide a plurality of fingers 20 and 21. The finger 20 extends into the notch 12 and the two fingers 21 40 which are bent outwardly engage the loop 10 to prevent the end of the finger 20 from projecting through the notch 12 to a point where it might engage the pin 9.

45 The spring loop 15 normally maintains the bowed parts 13 and 19 so that they diverge outwardly from the loop 10. Thus when the door is being hingedly moved with respect to the door jamb and the runs 13 and 19 are being drawn through the aperture 5, the runs 13 and 50 19 will engage the side edges respectively of the aperture 5 after the door has been moved to a certain point and movement of the door past this point will be resisted by the frictional contact of the runs therewith.

Movement of the door to the dotted line position shown in Fig. 2 will cause the shoulders 14 and 16 to engage the angular wall 4 of the socket 3 to prevent further movement of the door. However, at the time the shoulders 14 and 16 engage the wall 4 the check cushions the checking action due to the straightening of the bowed runs 13 and 19.

Movement of the door from its open position 10 to its closed position is checked by the shoulder 18 coming in contact with the opposite surface of the wall 4. This checking action is yieldable and is provided to prevent the door from swinging to its closed position as a result of a 15 rebounding action when the check functions to check the outward movement.

As the run 13 is initially placed under tension and it begins to straighten from its bowed position to its straight line position the loop 10 rotates relative to the pin 9. As the tension increases the loop 10 has a tendency to unwind itself from the pin 9 with the result that the metal at the point where the run 13 merges into the loop 10 is strained beyond its elastic limit 25 and the metal becomes fatigued at this point. In the present device, however, at the time the run 13 is placed under tension the run 19 is under compression with the result that the fingers 21 press against the loop 10 in a manner to prevent 30 this unwinding tendency. By preventing the unwinding tendency the metal no longer becomes fatigued at this point and the useful life of the check is increased.

Although a specific embodiment of the invention has been illustrated and described it will be understood that various changes may be made within the scope of the appended claims without departing from the spirit of the invention, and such changes are contemplated.

40 What I claim is:—

1. A door check comprised of a spring metal blank having a pin receiving loop at one end, the said blank extending continuously from said loop to respectively form a bowed run, a shoulder 45 at the termination point of said bowed run, a spring loop portion, a run extending in the direction of said receiving loop and connected therewith, and a shoulder between said last named run and said spring loop portion.

50 2. A door check comprised of a spring metal blank bent to provide a pin receiving loop at one end, said blank extending from said loop to provide a yieldable checking means and extending from said means back in the direction of said loop, the other end of said blank having a plurality of

separate fingers, one of said fingers being received in a notch in said loop, and at least one other of said fingers engaging the periphery of said loop.

5 3. A door check comprised of a spring metal blank having retainer receiving means and diverging runs extending outwardly from said means, said blank having a portion uniting the outer ends of said runs and yieldably holding them in their diverging relationship, said blank being formed with shoulders between said runs and said yieldable portion.

10 4. A door check comprised of a spring metal blank having retainer receiving means and diverging runs extending outwardly from said means, said blank having a portion uniting the outer ends of said runs and yieldably holding them in their diverging relationship, said blank being formed with shoulders between said runs and said yieldable portion, one of said runs being connected to said retainer receiving means whereby it is free to move in one direction with respect thereto.

15 5. A door check comprised of a spring metal blank having retainer receiving means and diverging runs extending outwardly from said means, said blank having a portion uniting the outer ends of said runs and yieldably holding them in their diverging relationship, said blank being formed with shoulders between said runs and said yieldable portion, one of said runs being connected to said retainer receiving means whereby it is free to move in one direction with respect thereto, and having means for engaging 20 said retainer receiving means to reinforce the same.

25 6. A door check comprised of a metal blank having a loop at one end, said loop having a notch therein, said blank extending from said loop to provide a bowed run, a shoulder, a spring portion, and a run extending outwardly from said spring portion, said last named run having a part received in said notch to hold said check in assembled relation.

30 7. A door check comprised of a metal blank having a loop at one end, said loop having a notch therein, said blank extending from said loop to provide a bowed run, a shoulder, a spring portion, a run extending outwardly from said spring portion, said last named run having a part received in said notch to hold said check in assembled relation, and means engaging said loop for restricting the movement of said part with respect to said notch.

35 40 45 50 55 REX C. JACOBS.
